UNITED STATES PATENT OFFICE

FRANK McMURRAY SAWYER, OF RICHMOND, VIRGINIA, ASSIGNOR TO FIREPROOF BUILDING CORPORATION, OF RICHMOND, VIRGINIA, A CORPORATION OF VIRGINIA

CONCRETE-BLOCK WALL CONSTRUCTION

Application filed June 10, 1929. Serial No. 369,343.

This invention relates to concrete block wall structures, and has for its objects to provide a particular shaped concrete block, which, upon arranging a plurality of them in 5 rows and tiers, will form a substantial wall and one wherein the blocks can be easily and effectually cemented together and be reinforced in a simple manner.

These and other objects hereinafter set 10 forth are accomplished by the means illustrated in the accompanying drawing, in which:

Fig. 1 is a perspective view of a portion of a wall structure embodying my invention.

15 Fig. 2 is a vertical cross-structural view taken on the line 2—2 of Fig. 3.

Fig. 3 is a horizontal sectional view taken on the line 3—3 of Fig. 2.

20 Fig. 4 is a perspective view of one of the slabs or blocks isolated from the wall and showing the arrangement of several of the reinforcing rods; and,

Fig. 5 is a detail perspective view of one of the transverse tie-members.

25 Similar reference numerals in all of the figures of the drawing designate like parts.

As shown in Fig. 1, the wall is preferably composed of an inner wall 10 and an outer wall 11 arranged in parallel relation and 30 spaced apart to form an insulating air space between them, and it will be observed that the blocks or slabs 12 are arranged in horizontal and vertical rows with their joints in alignment in both directions, and that the walls are 35 joined together by the tie-members 13 at the intersection of the vertical and horizontal joints.

Each block or slab 12 is formed at both its 40 vertical edges with a projecting vertical ledge 14 which extends approximately the full length of the edges, and the bases of the ledges lie slightly back of the edges, and said ledges are concaved on their outer sides to form a recess, which when the edges of one 45 slab is positioned close to the edge of an adjacent slab, will form a vertical pocket to receive a vertical reinforcing rod 15 and the uniting cement 16 which is poured therein to provide a vertical concrete column extending 50 the full height of the wall.

At the upper edge of the slabs is formed a projecting horizontal ledge 16', similar to the vertical ledges 15 and practically being a continuation of said ledges 14, and having its upper side concaved to receive the horizontal 55 reinforcing rods 17, so that, when the slabs are arranged edge to edge, the concaves of the horizontal ledges will form a series of open gutters extending continuously across the wall and the concrete filling 18 therein will 60 embed the horizontal rods 17 and unite with the concrete of the vertical columns 16.

Tie-members 13 are precast and are of any suitable cross section in form, preferably rectangular, as shown in the drawing, and they are reinforced their entire length by a tie-rod 19 whose ends project a considerable distance beyond the concrete portion so that they can be tied to the rods 15 and 17 at their intersections, as clearly shown in the drawings.

The wall is erected by assembling the wall slabs in courses and after each course is laid, mortar or grout is applied to the hollow spaces between the walls and in the gutters formed by the horizontal ledges, thereby filling every joint and covering all of the metal reinforcing rods and ties, thus providing a wall construction which is easily erected and aligned and connecting firmly all of the joints 70 and sealing them on the rear sides.

It will be understood that each of the building units used is preferably precast and, if desired, with a finished face, so that a finished wall can be laid without the use of any 75 other coating of plaster or the like.

The bed joint formed by the horizontal gutters is essential in that it provides a ledge to receive the sealing cement and it is obvious 80 that the cement can be applied easily and without mechanical or artistic skill. The bed joint is also designed to assist in aligning the wall and at the same time provides a watertight joint.

Having thus fully described the invention, 85 what is claimed is:

1. A concrete wall construction formed with a plurality of precast concrete slabs laid in superposed horizontal courses with their vertical joints in continuous alignment, a 160

vertical concrete column extending the height of the wall formed at the vertical joint between the slabs and between the meeting edges thereof, and a plurality of horizontal rows of concrete material formed in horizontal alignment with the horizontal meeting edges of the slabs and lying to the rear of the body portion of the slabs.

5. A concrete wall construction having inner and outer walls and each formed with a plurality of precast concrete slabs laid in superposed horizontal courses with their vertical joints in continuous alignment, a vertical concrete column extending the height of 10 the wall formed at the vertical joints between the slabs and between the meeting edges thereof, a plurality of horizontal rows of concrete material formed in horizontal alignment with the horizontal meeting edges of 15 the slabs and lying to the rear of the body portion of the slabs, each of said vertical columns and horizontal rows of concrete material being provided with reinforcing rods which intersect at the intersection of the 20 joints between the slabs, and transverse precast tie-members located at the intersection of the rod joints and formed with a reinforcing rod whose free ends are tied to the intersecting portions of the horizontal and vertical rods.

3. A precast concrete slab for wall construction, comprising a slab-like body portion having two parallel edges enlarged and formed with a recess to provide a hollow 35 space between adjacent slabs, another edge of the slab being formed with a projecting ledge on the rear side and said ledge being recessed at its outer side to provide a horizontal gutter to receive a concrete filling positioned at 40 the rear side of the wall.

40 In testimony whereof I affix my signature.
FRANK McMURRAY SAWYER.
